UNITED STATES PATENT OFFICE

GUSTAV J. SENGBUSCH, OF MILWAUKEE, WISCONSIN

DESIGN FOR A COMBINATION DESK STAND AND PENHOLDER

Application filed October 22, 1929. Serial No. 33,137. Term of patent 14 years.

To all whom it may concern:

Be it known that I, GUSTAV J. SENGBUSCH, a citizen of the United States, and a resident of the city of Milwaukee, county of Milwaukee, and State of Wisconsin, have invented a new, original, and ornamental Design for a Combination Desk Stand and Penholder, of which the following is a specification, reference being had to the accompanying drawing, forming part thereof.

The figure is a perspective view of a combination desk stand and penholder showing my new design.

I claim:

The ornamental design for a combination desk stand and penholder as shown.

GUSTAV J. SENGBUSCH.
